UNITED STATES PATENT OFFICE.

ROY E. GAINES, OF DALE, INDIANA.

COMPUTING YARD-MEASURE.

No. 866,125.

Specification of Letters Patent.

Patented Sept. 17, 1907.

Application filed September 19, 1904. Serial No. 225,092.

To all whom it may concern:

Be it known that I, ROY E. GAINES, a citizen of the United States, residing at Dale, in the county of Spencer and the State of Indiana, have invented a new and 5 useful Improvement in Computing Yard-Measures, of which the following is a specification.

This invention relates to a device for quickly and accurately computing the price per yard of goods sold by the yard, or of the amount of goods in yard lengths, or 10 fractions thereof, to be sold for a certain amount at a predetermined price per yard.

The invention consists of the novel features of construction and combination of parts hereinafter described, pointed out in the claims and shown in the accompanying drawings in which:—

Figure 1 is a plan view of the yard stick, partly broken out. Fig. 2 is a plan view of the yard stick showing the reverse side to that shown in Fig. 1. Fig. 3 is a fragmentary portion of the yard stick showing the 20 movable slide thereon, the parts being in plan. Fig. 4 is a detail front face view of the slide. Fig. 5 is a section on the line 5—5 of Fig. 3.

In the drawings A represents a yard stick having at one end a handle A', and having along its longitudinal 25 edges and on each face a scale in inches and fractions of an inch as shown at B. On each face between the scales C B are a plurality of longitudinally extending lines C preferably nine in number dividing the faces of the yard stick into ten longitudinally extending spaces.

30 Each of these spaces are divided into fractional parts as indicated by the transverse lines D.

I further provide a flat sleeve E which is adapted to slide upon the yard stick A. The end marginal portions of the sleeve E are notched or indented as shown 35 at E', and longitudinally the edges of the sleeve E, on each face are divided into a plurality of spaces E' by suitable divisional lines. The central portion of the faces of the sleeves, between the marginal spaces E' are divided by longitudinal and transverse lines into a 40 plurality of spaces E² in which numerals are imprinted as shown at E², and it is further understood that any desired characters, numerals and signs are imprinted on the yard stick and sleeve as may be found desirable or necessary for the particular use to which the device is

45 to be put, which characters, numerals and signs may vary in different instruments according to the class of business in which they are used as will be more fully set forth in the explanation of the manner of using this invention. It will be noted from Fig. 3 that the recesses E⁴ of the slide E align with the spaces formed 50 upon the yard stick by the lines C and that the short perpendicular lines D can be brought into register with the said recesses by moving the slide backward and forward, and that the handle A' facilitates the use of the 55 slide at the right hand end of the yard stick A.

The operation of the device is as follows: Numerals in

the spaces E' designate multiples of a yard, and the numerals in the spaces E² designate prices for one or more yards, the numerals adjacent the recessed ends representing the prices of various grades or kinds of 60 goods per yard, and the second column from the left under the numeral 2 representing the price of two yards at the same rate per yard. The perpendicular lines D indicate one or more cents, reading from right to left, each fifth line—in the order named, being marked with 65 suitable numerals to facilitate reading. Assuming therefore that a certain piece of goods is worth thirty cents per yard and a customer desires twenty-five cents' worth of the goods at that price. By moving the slide E on the yard stick A until the recess E⁴, in longitudinal 70 alinement with the space E² having the numerals thirty imprinted therein, registers with the line D marked "25" the corners of the slide in alinement with the said line D will designate thirty as the number of inches of cloth to be given. In the same way if thirty 75 inches of the cloth at thirty cents per yard had been desired, the slide would have been moved to the same line and the price, twenty-five cents, would have been indicated. Should a customer desire fifteen cents' worth of goods from a piece worth twenty cents per 80 yard the proper recess E⁴ is moved until it registers with "15" on the yard stick and the length of the piece will be indicated as twenty-seven inches.

To prevent crowding the lines and numerals I arrange one side of the yard stick and slide to compute 85 prices from five to fifty cents, and the opposite side from fifty cents to one dollar, and a number of series of instruments may be provided each series computing prices between certain predetermined rates. This arrangement will be found advantagous in the case of 90 department stores where the goods are classified. For example in a ribbon department where the goods will range in price from a few cents to a dollar a yard stick and slide will be provided adapted for computations within that range, and in other departments where 95 other prices will prevail the stick A and slide E will have imprinted numerals adapted to compute at those prices, as it is immaterial what arbitrary designations may be assigned to the various lines and spaces.

Having thus fully described my invention what I 100 claim as new and desire to secure by Letters Patent is:—

A computing yard measure comprising a yard stick having a linear scale thereon, a plurality of transverse lines on said stick having the requisite numerals to represent the fractional costs, and a slidable, notched sleeve on said stick, the notches registering with the transverse lines, and the said sleeve bearing a plurality of numerals designating total cost, said numerals alining with the notches. 105

ROY E. GAINES.
